[57] CLAIM

The ornamental design for an electrical switchgear enclosure for power distribution systems, as shown and described.

DESCRIPTION

FIG. 1 is a perspective view of an electrical switchgear enclosure for power distribution systems showing our new design;

FIG. 2 is a front elevational view thereof, the rear elevational view being identical thereto;

FIG. 3 is a right side elevational view thereof, the left side elevational view being identical thereto; and,

FIG. 4 is top plan view thereof.
